UNITED STATES PATENT OFFICE.

MARK A. PENNEY, OF DES MOINES, IOWA, ASSIGNOR TO WILLIAM L. CARPENTER, OF SAME PLACE.

BARB-WIRE-FENCE MACHINE.

SPECIFICATION forming part of Letters Patent No. 293,778, dated February 19, 1884.

Application filed April 16, 1883. (No model.)

To all whom it may concern:

Be it known that I, MARK A. PENNEY, a citizen of the United States, residing in Des Moines, in the county of Polk and State of Iowa, have invented a new and useful Improvement in Barb-Wire-Fence Machines, of which the following is a specification.

This invention relates to machines for the manufacture of barb-wire fencing. I have endeavored in devising it to produce a simple, strong, and inexpensive machine, capable of being run at a uniform high rate of speed.

The nature of the invention will be fully comprehended from the following description; and it consists in the novel construction and combinations set forth.

In the accompanying drawings, forming a part of this description, Figure 1 is a plan of my improved machine. Fig. 2 is a side elevation, with the frame partially broken away to show the various movements. Figs. 3, 4, and 5 are transverse sections on the line 3 3, line 4 4, and line 5 5, respectively, of Fig. 1. Fig. 6 is a vertical longitudinal section through the barb-severing devices. Figs. 7 and 8 are horizontal sections upon lines 7 7 and 8 8, respectively, of Fig. 6. Fig. 9 is a plan of the lower knife. Fig. 9^a is a bottom view of the cap covering the guide upon the lower knife. Fig. 10 is a bottom longitudinal section of the coiling-cylinder, and Fig. 11 shows the rack and pinion for actuating the barb-feed rolls.

The wire passes into the machine from two coils supported on bracket A', bolted to the main frame A, and enters first between the grooved feed-rolls B B and B' B', which are geared together by gears B² B³ upon the same shafts, b b', therewith, and intermittent motion is imparted to said rolls by the pins c upon the wheel C, and the cam C' fastened on the main shaft D. This cam C' is provided with a rim, continuous except at one point, where its ends are turned out laterally in opposite directions, and it revolves in the spaces between the pins c, as clearly illustrated, moving the pin-wheel one space at each revolution. The main shaft is actuated by bevel-gears D' D², shaft D³, and belt-pulley D⁴. That one of the wires which is fed by rolls B B issues from thence to the hollow spindle E,

supported on bearings e e, and to which a continuous rotation is given by pinion e', intermediate gear, e², and large gear e³ on the main shaft. Said intermediate wheel is supported 55 upon a bracket, e⁴.

Upon the forward end of the spindle E is a sleeve, E', keyed to the spindle by the feather E², so as to rotate therewith, but fitted thereon with sufficient freedom to allow it to reciprocate to a limited extent independently of the spindle, though it also reciprocates therewith. The feather E² is dovetailed in the sleeve, and it or a pin upon it operates to coil the barbs on the wire. A spring, E³, presses 60 the spindle forward to the extent permitted by the contact of the collar E⁴ with the standard e, and when thus pressed forward with the coiling-feather in advance, as in Fig. 10, the parts are in position to seize and coil the barb. 70 After the coiling, the sleeve is retracted by the sliding bar, E⁵, which carries a fork or clutch, e⁶, upon its forward end, fitting into the annular groove e⁷ upon the sleeve, the power for this function being carried to said bar from 75 the grooved cam E⁸ on the main shaft through the medium of the roller or stud e⁹, crank-arm e¹⁰, shaft or spindle e¹¹, confined in the hollow upright e¹², the lateral arm of the bell-crank lever e¹³, and pin e¹⁴. The cam E⁸ is so fashioned that it retains the coiler in the retracted position long enough for the barb to be severed and the fence-wire to be fed forward a barb-space. The spindle does not retract with the sleeve until the latter strikes the shoulder 80 e¹⁵ upon the former, thus having a more limited reciprocation than does the sleeve. This differential reciprocation of the two parts is provided in order that the spindle may continue to serve as a sort of guide or abutment 85 to the end of the barb after the withdrawing movement of the coiling-pin has commenced, and insures the projection of the barb-point at right angles to the main wire. When the time arrives for coiling the next barb, the sliding 90 bar E⁵ is actuated in a forward direction by the same mechanism, and carries the sleeve with it into position for that operation, while at the same time the spring returns the spindle, and both sleeve and spindle are left to 95 rotate in this position until the barb is coiled. The spring also holds the spindle in the ad-

vanced position during the coiling. The barb-wire is fed in during the advance of the fence-wires by the feed-rolls F F', the shafts f of which are geared together by gears F' F'. The lower shaft, f, has also a loose gear, F'', with flange f'', carrying a pawl, f³, engaging with a ratchet-wheel, f⁴, keyed fast to the same shaft. By means of these, said feed-rolls receive periodical motion from the rack F⁵, which is operated by the bell-crank F⁶, actuated by the cam F⁷ upon the main shaft, said crank having upon one arm a suitable stud or roller fitting into the groove of said cams, and being connected to the rack by the other arm. The lower knife, G, for cutting off the barb-wire is fitted and confined in a groove in the sliding head G' by the cap g, and is adjusted vertically therein by means of the screw g'. A guide, g², for the barb-wire is placed directly over the knife, but not so as to cover the cutting-edge thereof. It is a narrow piece of flat metal, the inner end acting to direct the barb and the outer end being bent down at right angles, as shown. It is adjusted by the screw 25 g³ and held by the cap g', the under side of the cap being grooved at m to admit the barb-wire. The head G' is actuated by the side groove-cam, G², upon the main shaft, and is first raised thereby to cut off the barb, then lowered to let the barb pass, then raised enough to allow the guide g² to guide the next barb while it enters and is being coiled, and is held in this latter position until again raised to cut. It is connected to the cam by the bar g⁵ carrying the stud-roller g⁶. The gibs g⁷ g⁸ are employed to take up wear. The upper knife, H, is fitted in a head, H', and held therein by a cap, h. Said head is oscillated upon the center of motion h' by means of the horizontally-sliding 30 bar h², to which it is connected by a pin, h³, and said bar is actuated by the forward arm of the bell-crank lever e'' (the same lever by which the coiling device is reciprocated) through the medium of the pin h⁴. The lower knife-head 35 slides in and the upper head is centered upon the bracket H², and the former is confined therein by guides h⁵, and the latter is confined upon its center of motion by the cap h⁶, the screw h⁷, and the washer h⁸. After the barb 40 is coiled, the upper knife is swung to a position directly over the lower knife, which then rises and severs the barb, after which both knives are withdrawn, as already described, to give room for the coiling-head as it advances 45 to coil the succeeding barb. Just before entering the hollow journal I of the twister, the wire upon which the barbs are placed is joined by the companion wire passing through feed-rolls B' B', and the two are then twisted together. The twister is actuated by the gears 50 I' and I² from the main shaft, and is supported by the pedestal I³, as shown. The shafts of the main feed-rolls and barb-feed rolls are sup-

ported in bearings K and L, respectively. The former are placed upon the upright rods 65 K', the bearings of the bottom rolls being secured upon said rods by set-screws k, while the top rolls are forced downward with sufficient power to move the wires by the screw k' and spring k². On the barb-feed rolls the pressure-screw l is placed directly over the bearing next to the rolls, as illustrated.

I claim—

1. In a barb-fence machine, a sliding coiler and oscillating knife-head, both combined with and connected to the same bell-crank lever, substantially as specified, whereby when the coiler is advanced the head is oscillated to make room for the coiler. 75
2. In a barb-fence machine, the severing devices, consisting of an oscillating knife and a reciprocating knife, combined and operating substantially as specified. 80
3. The combination of the sliding spindle, the sleeve carrying a coiler, and secured upon the spindle so as to rotate therewith, the gear rotating the spindle, and the bar retracting both sleeve and spindle, substantially as specified. 85
4. The combination, with the coiler and spindle, of the bar E², crank-arm e'', spindle e², crank e³, and cam E⁴, substantially as specified. 90
5. The combination, with the oscillating knife-head, of the sliding bar h², crank-arm e'', spindle e², crank e³, and cam E⁴, substantially as specified. 95
6. The spindle, actuated in the forward direction by a spring, and having a shoulder, e¹³, and a sliding sleeve mounted on said spindle and engaging with said shoulder, and actuated in both directions by the sliding bar, in combination with the spring and sliding bar, substantially as specified. 100
7. The forked bar E⁵ and its actuating devices, in combination with the coiler, the spindle, and the spring E³, substantially as specified. 105
8. The combination, with the lower knife-head, of the barb-guide g², substantially as specified. 110
9. The combination, with the lower knife-head, of the barb-guide g², provided with the adjusting-screw g', substantially as specified. 115
10. The combination, with the lower knife-head and the guide carried thereby, of the cam G² and the connecting-bar, whereby said head and guide, after the cutting off of the barb, are first lowered, then raised partially, and then raised completely for the severance 120 of the next barb, substantially as specified.
